INVENTOR

Emery Parker

United States Patent Office.

EMERY PARKER, OF NEW BRITAIN, CONNECTICUT, ASSIGNOR TO THE RUSSELL AND ERWIN MANUFACTURING COMPANY, OF SAME PLACE.

Design No. 3,534, dated June 8, 1869.

DESIGN FOR THE FACE-PLATE OF A HINGE.

The Schedule referred to in these Letters Patent and making part of the same.

To all whom it may concern:

Be it known that I, EMERY PARKER, of New Britain, in the county of Hartford, and State of Connecticut, have originated and designed a new Design for Face-Plate for Hinge; and I do hereby declare that the following is a full, clear, and exact description thereof, reference being had to the accompanying drawings, making a part of this specification.

In the drawings—

Figure 1 represents a door-hinge, the leaves of which are covered by an ornamental face-plate.

The leaf A shows the complete design.

The leaf B is deficient in the central shield, which is shown separately at Figure 2.

The edge of the plate is surrounded by a band, a, which may be raised or otherwise, and be plain, or some ornamental moulding.

The central portion is a shield, C, which bears upon its face a monogram.

The remaining space is filled with ornamental work in relief, upon either a plain or matted ground.

The design is intended to be employed in those cases where a distinctive character is to be given to the door-hinges, by causing them to bear the monogram of the owner, to correspond with a like monogram with which mirror-frames, library-cases, and the arched heads of door-ways are often ornamented.

For convenience, the pattern from which the design is to be made has the central shield removable, so that different centre-pieces, bearing different monograms, can be used with the same pattern.

What I claim as my invention, and desire to secure by Letters Patent, is—

The design for a hinge-plate, consisting of the edge-band or moulding a, the central-shield C, bearing a monogram of letters, and the space between the shield and the edge-band filled with ornamental scroll-work in relief, all substantially as herein described and shown.

EMERY PARKER.
